UNITED STATES PATENT OFFICE.

EDWARD D. BACH, OF ARDMORE, OKLAHOMA.

AUTOMATIC PRESSURE-OPERABLE VALVE.

Application filed November 28, 1923. Serial No. 677,452.

To all whom it may concern:

Be it known that I, EDWARD D. BACH, a citizen of the United States, residing at Ardmore, in the county of Carter and State of Oklahoma, have invented certain new and useful Improvements in an Automatic Pressure-Operable Valve; and I do hereby declare the following to be a full, clear, and exact description of the invention, such as will enable others skilled in the art to which it appertains to make and use the same.

This invention relates to a valve and particularly to one adapted for automatic control by the pressure in the pipe line or otherwise where it is installed or used.

A particular object of the present invention is to provide a valve which is so arranged as to allow any desired amount of pressure to accumulate in a line before it releases to shut off at any desired pressure.

Another object is to provide such a construction in which the pressure applied to a diaphragm to operate the valve may equalize after closing of the valve with the pressure on the low-pressure side of the valve.

Various additional objects and advantages will become apparent from a consideration of the description following taken in connection with the accompanying drawings illustrating an operative embodiment.

In said drawings:

Figure 1 is a view in side elevation illustrating the improved valve;

Figure 2 is a plan view;

Figure 3 is an end elevation taken at a right angle to Figure 1;

Figure 4 is a substantially central vertical sectional view taken at a right angle to

Figure 3;

Figure 5 is a sectional view on the line 5—5 of Figure 1;

Figure 6 is a sectional view on the line 6—6 of Figure 1; and

Figure 7 is a substantially vertical sectional view taken on the line 7—7 of Figure 3 and showing the pressure control valve in detail.

Like reference characters designate like or similar parts in the different views.

Referring specifically to the drawings, the valve has a casing 10 which is detachably or otherwise connected in any suitable manner as at 11 to pipe sections 12 in which material is adapted to flow in the direction of the arrows as indicated in Figure 4, and

for instance from a container, water well, oil well, gas well or otherwise. Appropriately arranged within the casing 10 and integral with it is a web 13 having spaced walls 14 through which ports or openings 15 are provided. The ports 15 are adapted to be closed by valves 16 carried by a stem 17. As a plurality of the valves 16 are employed, if one does not efficiently close its seat or port 15, the other one will and thus an effective closing on the part of the valve 16 is assured. Stem 17 is vertically slideable through a suitable packing box 18 at the top of the casing and is in sections 18^a and 18^b joined by threaded engagement with a turn-buckle 19 which is operable to vary the length of the valve.

The upper end of section 18^b has connection as at 20 to a flexible diaphragm 21. Diaphragm 21 is fastened as by a ring 22 and set screws 23 to a depending flange 24 of a casing 25 which extends forwardly from and is integral with an arm 26 also integral with and rising from the casing 10. The casing 25 in combination with the diaphragm 21 provides an hermetic chamber 27 between the same.

An upstanding pipe 28 leads from the casing 10 in front of the web 13 to a pressure control valve generally designated 29 from which a pipe 30 leads to a T 31 having a branch pipe 32 extending therefrom and to a raised portion 33 of the casing 25 to the end that pressure from the material flowing through the pipe 12 may pass through the pipes outlined and valve 29 into the chambers 27 in order to centrally depress or expand the diaphragm 21 and cause the same to correspondingly slide the stem 17 and open the ports 15.

Valve 29 may be of any suitable construction but one capable of regulation. To this end it has a casing 29^a enclosing a head or valve proper 34 having a gasket 34^a. The head 34 is normally held against its seat 34^b by an expansive coil spring 35. The valve 34 is adapted to open by the pressure in pipe 28 upon the latter reaching a predetermined degree, dependent upon the tension of the spring 35. Spring 35 therefore is adapted to be tensioned in order to control the opening of this valve. To this end, a plug 36 is threaded to the casing 29^a and engages the spring 35. Head 34 has a stem 37 slidably disposed in the plug 36 and exteriorly of the valve provided with a hand wheel 31^a. Thus

according to the position of the stem and disk 37, the tension of spring 35 is varied.

A pipe 38 extends from the T 31 and is coupled to an upstanding pipe 39 which communicates with the interior of casing 10 in the rear of the web 13. Pipe 38 may have a cut off valve 40 therein.

In order to maintain the valve 16 normally seated, a lever 41 is employed which 10 is pivoted at 42 to an arm 43 integral with and extending forwardly from the arm 26. One end of the lever 41 is disposed in the opening of turn buckle 19. A weight or poise 42' is adjustable along the lever 41 and 15 is used to maintain the valves 16 seated and the stem 17 elevated.

In operation, with all of the valves closed, the device is set for opening of the valves 16 at a predetermined pressure, according 20 to the regulation of the stem 36 or tension of spring 35. Upon the accumulation of such pressure, the same will enter the pipe 28, unseat disk 34 and flow through pipe 30, T 31, partly into pipe 38 but sufficiently 25 into pipe 32 and then into chamber 27 so as to expand the diaphragm 21, depress the stem 17 against the urgency of weight 42, thus lowering the valves 16, uncovering the ports 15 and establishing communication 30 through the casing 10 with the pipe sections 12. The pressure is thus relieved. After such operation of the diaphragm 21, the pressure in chamber 27 will be relieved or 35 equalized with the pressure in the casing 10 and pipe 12 in front thereof, through the pipe 38 and pipe 39, the degree of equalization being controlled by the valve 40. Such valve 40 is particularly desirable in order to reduce the size of opening 39 after ex-

pansion of the diaphragm, so that the pressure will not be trapped and the back pressure will not hold down the diaphragm 40 uniformly.

Changes may be resorted to provided they fall within the spirit and scope of the invention. 45

Having thus described the invention, what I claim is:

A valve having a casing, a valve member therein, a stem extending from said valve member and exteriorly of the casing, a diaphragm associated with said stem, a casing disposed over the first mentioned casing and to which said diaphragm is secured and forming a pressure chamber, means for the admission of pressure to said chamber including pipe means having a valve adjustable to open at different pressures and for connection on the high pressure side of the valve, and pipe means leading from said pipe means for connection to the low pressure side of the valve, and a regulable valve in the last mentioned pipe means, an arm integral with both of said casings, a weighted lever pivoted to said arm, said stem being 60 in sections, a turn buckle connecting said sections and engaged by said lever, said lever being disposed between the arm and pipe means and terminating outwardly to one side of the latter, said lever serving to 65 maintain the valve normally closed.

In testimony whereof I affix my signature in presence of two witnesses.

EDWARD D. BACH.
